Primary Examiner — Michael A. Pratt(74) *Attorney, Agent, or Firm* — Banner & Witcoff, Ltd.(57) **CLAIM**

The ornamental design for a vanity mirror for vehicles, as shown and described.

DESCRIPTION

FIG. 1 is a perspective view of a vanity mirror for vehicles showing our new design;

FIG. 2 is a front view thereof;

FIG. 3 is a left side view thereof;

FIG. 4 is a plan view thereof; and,

FIG. 5 is an alternative perspective view thereof.

The broken line showing of the various unshaded elements of a vanity mirror for a vehicle represents unclaimed subject matter and forms no part of the claimed design.
